POWER-TRANSMISSION GEARING.

1,332,708.

Specification of Letters Patent.

Patented Mar. 2, 1920.

Application filed November 4, 1919. Serial No. 335,769.

To all whom it may concern:

Be it known that I, GUNNAR ELIAS CASSEL, a citizen of the Kingdom of Sweden, residing at Djursholm, Sweden, have invented 5 new and useful Improvements in Power-Transmission Gearings, of which the following is a specification.

For the transmission of power between shafts lying in alinement with one another 10 it has been proposed, in order to obtain a great ratio of gearing by means of a compact and reliable gearing, to use a gearing comprising a gyratorically swinging thrust disk mounted on one of the shafts and having 15 a plurality of radial projections, a casing or drum surrounding the thrust-disk and having an endless cam slot engaged by the said projections, and a guide-way causing the disk to move in an axial plane one 20 of the said last-mentioned elements, viz. the drum or the casing, being secured to the other shaft, while the other of said elements is mounted stationary.

When the thrust-disk is thus caused to 25 move in an axial plane, it has been found that different points of the disk will follow different paths in the movement of the disk so that not more than two projections of the disk—provided they are diametrically opposite—may engage the same endless slot 30 of the drum. To suitably distribute the power output of the disk it is, however, necessary to provide more than two projections so that two separate slots at least must be 35 formed on the drum. As said slots will not be completely independent of each other but will partly coincide the slots must be situated at different radial distances from the center of the disk thereby rendering the 40 making of the slots difficult and giving but comparatively small contact surfaces in each slot.

In order to overcome said difficulties, the 45 guide-way is formed, according to this invention, in such a way that all points of the disk will describe equal paths in the movement of the thrust-disk. This will result in that a plurality of projections of the thrust-disk may engage one and the same slot of 50 the drum, moreover, it will be possible to use a plurality of equal guide-ways for the drum, preferably uniformly distributed around the drum so that the load on the thrust-disk will be uniformly distributed to 55 the greatest extent possible.

In the accompanying drawing, one embodiment of the invention is illustrated. Figure 1 shows a longitudinal section, and Fig. 2 shows a cross section of a gearing embodying this invention, while Fig. 3 shows a detail.

With reference to the drawing, the numerals 1 and 2 indicate two shafts lying in the alinement of one another and being exactly centered with respect to each other. 65 The shaft 1 carries an obliquely arranged disk-shaped driving member 3 keyed to the shaft and carrying a thrust-disk 4 by means of thrust bearing balls 5 and 6. The disk 4 is provided with four symmetrically disposed radial projections 7 formed as sleeves or cups in which radially extending rollers 71 are mounted by means of balls. The rollers 71 are formed at their outer ends with disk-shaped heads 8, engaging an endless cam slot 9 formed in the inner surface of a stationary drum surrounding the disk 4. The end walls of said drum form bearings for the ends of the shafts 1 and 2. 75

Formed between the projections 7 are projections 11 carrying antifriction rollers 12 each engaging a separate guide-way formed by a slot 14 in an arm 13 rigidly secured to the shaft 2. The guide-arms 13 extend axially, the slots 14 thereof being, however, not 80 straight inasmuch as the fundamental form of the slot consists of an eight, as indicated by dotted lines in Fig. 3, which shows a guiding arm 13 seen from the shaft. The said form of the slot 14 is so chosen that all 85 points of the thrust-disk will describe equal paths in the movement of the thrust-disk. Owing thereto, a plurality of projections of the thrust-disk may engage one and the same slot of the drum, the number of such projections depending only on the number of 90 waves of the slots. Furthermore, any desired number of projections 11 and guiding arms 13 may be provided so as to obtain a 95 uniform loading of the thrust-disk when in operation.

Assuming the shaft 1 is the driving shaft, the disk 4 will upon the rotation of the shaft 1 be caused to perform a swinging movement corresponding to a wave-movement 105 proceeding along the periphery of the disk. Due to the engagement of the projections 7, 8 with the stationary cam-slot 9, the disk 4 is caused to perform a circumferential movement the number of waves of the slot 9 de- 110

termining the ratio of gearing inasmuch as each projection 7, 8 will at each revolution of the shaft 1 pass through one wave of the slot 9. Owing to the engagement of the 5 projections 11 with the guiding arms 13, the shaft 2 will be caused to follow the disk in its peripheral movement but while the thrust disk does not move with a uniform speed, the shaft 2 due to the special form of 10 the guiding slots 14 will be rotated continuously.

The form of the guiding slots 14 above described may be obtained either experimentally or mathematically. The method 15 of obtaining said form forming no part of this invention will not be described herein.

What I claim is:—

1. A power transmission gearing for shafts being in alinement with one another, 20 comprising an oblique disk, attached to one of said shafts, a thrust-disk loosely mounted on said oblique disk and performing a gyroscopic swinging movement during the rotation of said shaft, a drum inclosing the 25 thrust disk and having an endless cam slot, radial projections on said thrust-disk engaging in said slot, guide-ways, other radial

projections on said thrust-disk engaging in said guide-ways, said guide-ways and said casing being adapted to perform a rotation 30 with relation to each other during the gyroscopic movement of the thrust-disk, the said guide-ways having such shape that all points of the thrust-disk will describe equal paths during said movement.

2. A power transmission gearing, comprising a rotary shaft, an oblique disk attached to said shaft, another disk loosely mounted on said oblique disk, radial projections on said thrust-disk, a stationary casing inclosing the thrust-disk, and having an endless cam slot on its inner surface, engaged by some of said projections, another shaft, lying in alinement to the said first-mentioned shaft, arms attached to said other shaft and having guiding slots formed therein engaged by projections of said thrust-disk, the shape of said slots being such as to cause all points of the thrust-disk during the rotation of said first-mentioned 45 shaft to perform movements in equal paths.

In testimony whereof I have signed my name.

GUNNAR ELIAS CASSEL.
